[57] CLAIM

The ornamental design for a seat for an upper body exercise machine, as shown and described.

[**] Term: 14 Years

DESCRIPTION

[21] Appl. No.: 361,095

FIG. 1 is a perspective view of a seat for an upper body exercise machine showing our new design;

[22] Filed: Jun. 5, 1989

FIG. 2 is a top plan view thereof;

[52] U.S. Cl. D21/191

FIG. 3 is a front elevational view thereof;

[58] Field of Search D21/191-199;

FIG. 4 is a side elevational view thereof; and

D6/374, 375; 272/144, 143, 73

FIG. 5 is a rear elevational view thereof.
